UNITED STATES PATENT OFFICE.

EDGAR M. WINFREY AND ALBERT G. BRANHAM, OF FORT WORTH, TEXAS.

REIN-HOLDER.

SPECIFICATION forming part of Letters Patent No. 340,849, dated April 27, 1886.

Application filed March 10, 1886. Serial No. 194,745. (No model.)

To all whom it may concern:

Be it known that we, EDGAR M. WINFREY and ALBERT G. BRANHAM, citizens of the United States, residing at Fort Worth, in the county of Tarrant and State of Texas, have invented certain new and useful Improvements in Driving-Rein Holders; and we do hereby declare that the following is a full, clear, and exact description of the same, reference being had to the annexed drawings, making a part of this specification, and to the letters and figures of reference marked thereon.

Figure 1 of the drawings is a perspective view of our invention, and Fig. 2 a cross section thereof.

The present invention has relation to that class of driving-rein holders in which a bracket is employed for attaching to the dash-board of the vehicle, and provided at one end with a standard, to which is pivoted a swinging jaw held down in position to hold the reins by means of a spring coiled around the pivot, the jaw having a convex corrugated face to more securely hold the reins.

It is the object of the present invention to improve the construction of the above class of driving-rein holders; and it consists in the construction substantially as shown in the drawings, and hereinafter described and claimed.

In the accompanying drawings, A represents the stationary jaw of the rein-holder, formed with a perforated fastening-shank, B, which may be attached either by screws or rivets in a vertical or horizontal position to any part of the vehicle preferred. The shank B is cast with a standard, C, which is provided with an L-shaped stop, a, on one side, and a fulcrum-rod, b, on the opposite side.

To the standard C is connected a frame, D, formed with a jaw, E, which moves with the frame, the latter being pivotally connected to the standard by an adjusting-rod, F, screw-threaded at one end, and provided with a suitable head at the other. The rod F passes loosely through perforations in the frame D, and the screw-threaded end thereof engages with a screw-threaded hole in the standard C, thereby admitting of the endwise adjustment of the frame to bring the end in frictional contact with the side of the standard to a greater

or less degree, as found desirable, to take a portion of the strain off the spring G; or, by unscrewing the rod F to a slight extent, the bearing portion of the rod in a longitudinal direction is increased, allowing the frame D to hang suspended on the rod without any frictional contact with the standard, thus depending wholly on the action of the spring. The spring G is coiled around the rod F, one arm thereof entering into a perforation, e, in the jaw E, and the other arm of the spring having a hook, d, to catch under the fulcrum-rod b.

The faces of the jaws A E are serrated, and the serrated face of the former is at an acute angle from a perpendicular, so that when the reins are held between the jaws any pull thereon will be at an angle corresponding with the incline of the face of the stationary jaw. In connection with the serrated face of the jaw E, which is on an arc of a circle or convex in form, the flat and angular serrated face of the jaw A will cause the jaws to bite the reins much harder.

A lug, e, having one or more perforations and depending from the under side of the jaw A, may be employed as an additional fastening for the device when required.

The ends of the jaws A E are conical or beveled, as shown at f, to form a space between them at their extremities, to facilitate the insertion of the reins between them.

A rein-holder constructed as above described is both simple and effective, and there is no danger of it getting out of order, and is equally applicable to all classes of vehicles, street-cars, and farm-machinery when a team is hitched thereto.

In using the device the driving-reins are first pulled toward the driver, and are slipped between the jaws A E, this being facilitated by the conical shape of the end of the jaws, as shown at f, the pressure of the upper jaw upon the reins holding them securely, and to remove the reins they are drawn toward the driver and upward, the upper jaw thereby loosening its grip, when the reins may be slipped out from between the jaws.

Having now fully described our invention, what we claim as new, and desire to secure by Letters Patent, is—

In a driving-rein holder, a stationary gripping-jaw having an inclined serrated face, a shank extending out to one side in a horizontal direction to provide means for attaching the holder to the dash-board of the vehicle, a standard provided with a fulcrum-rod and stop, in combination with a movable jaw having a convex serrated face, a frame formed thereon, an adjusting screw-rod connecting the frame to the standard, and a spring coiled around said rod, one end of the spring hooked around the

fulcrum-rod and the opposite end entering a perforation in the movable jaw, substantially as and for the purpose set forth.

In testimony that we claim the above we have hereunto subscribed our names in the presence of two witnesses.

EDGAR M. WINFREY.
ALBERT G. BRANHAM.
